PYROPHORIC LIGHTER MECHANISM

Carl Julius Lagerholm, Attleboro, Mass., assignor
to Evans Case Company, North Attleboro,
Mass., a corporation of Massachusetts

Application August 16, 1933, Serial No. 685,308

23 Claims. (Cl. 67—7.1)

The invention relates to pyrophoric lighters and, with regard to the more specific features thereof, to a pyrophoric lighter mechanism burning solid fuel.

One object of the invention is to provide an efficient mechanism for burning solid fuel. Another object of the invention is to provide a lighter adapted to consume solid fuel in which the fuel can readily be replenished. Another object of the invention is to provide a simple and effective feeding device for the solid fuel. Another object of the invention is to provide a lighter mechanism in which various actions automatically occur in a given sequence. Another object of the invention is to provide a lighter mechanism utilizing a catalytic agent in which the catalytic agent is held in engagement with the fuel during the sparking operation and then removed therefrom. Other objects will be in part obvious or in part pointed out hereinafter.

The invention accordingly consists in the features of construction, combinations of elements and arrangement of parts as will be exemplified in the structure to be hereinafter described, and the scope of the application of which will be indicated in the following claims.

In the accompanying drawings, in which is shown one of various possible embodiments of the mechanical features of this invention,

Figure 1 is a perspective view of a lighter embodying the invention;

Figure 2 is a plan view of the lighter;

Figure 3 is a vertical sectional view taken on the line 3—3 of Figure 2 looking in the direction of the arrows;

Figure 4 is a vertical sectional view taken on line 4—4 of Figure 2 looking in the direction of the arrows;

Figure 5 is a view similar to Figure 4 showing the finger piece partially depressed and the snuffer partially elevated;

Figure 6 is a view similar to Figure 5 showing the finger piece fully depressed and the snuffer fully elevated;

Figure 7 is a perspective view of the finger piece detached from the lighter;

Figure 8 is a perspective view of the snuffer detached from the lighter;

Figure 9 is a perspective view of the catalytic agent carrying member;

Figure 10 is a plan view of a detent and a cross-section of the fuel tube;

Figure 11 is a fragmentary plan view of a more modified form of lighter showing a direct drive between the finger piece and the sparking wheel;

Figure 12 is a fragmentary perspective view of one arm of the finger piece according to the modification of Figure 11;

Figure 13 is a side elevation of the sparking wheel of Figure 11; and

Figure 14 is a vertical sectional view showing a further modification of the invention involving a manually operable feeding device for the solid fuel.

Similar reference characters refer to similar parts throughout the several views of the drawings.

Referring now more particularly to Figure 3, I provide a casing 20 which desirably consists of a pair of shells suitably fastened together as by solder, the dividing line between the shells (which is scarcely discernible in the finished article) being indicated by the dotted line 21 in Figure 1. The casing 20 is closed at the bottom by a bottom wall 22 which has four orifices 23, 24, 25 and 26. The orifice 23 has secured in it, desirably by solder, the lower end of a tube 27. Likewise the orifices 24, 25 and 26 have secured in them tubes 28, 29 and 30 respectively. The bottom of each tube is closed by a threaded screw plug, 10 these plugs being designated by the reference characters 31, 32, 33 and 34 respectively for the tubes 27, 28, 29 and 30.

Referring now to Figures 3 and 4, the top of the casing 20 is closed by a top wall flange 35 25 which may be secured to the casing 20 by solder. The tube 27 extends through the top wall flange 35, the tube being located near one end of the lighter as shown in the drawings, and having an integral flange 36 with a seat 37 for a snuffer 30 cap 38 which will be hereinafter more fully described. The tube 28 contains a spring 39 the upper end of which is coiled about the shank of a plunger 40 engaging a piece 41 of pyrophoric metal or other substance adapted to produce 35 sparks. Referring particularly to Figure 3, the bottom end of the spring 39 is coiled about the knob 42 formed on the upper end of the screw plug 32. By unscrewing the plug 32 the spring 39, the plunger 40 and the pyrophoric metal 41 40 may be removed from the tube 28 at any time for the purpose, for example, of replacing a used piece of pyrophoric metal with a fresh piece.

Referring now to Figure 3, extending downwardly from one end of the top wall flange 35 45 and soldered to the inside of the casing 20 is an irregular supporting member 43. The tube 28 extends through and is supported by the member 43, and the upper end of the tube 28 is supported by a platform 44 extending inwardly from 50 the flange 35.

Referring now to Figures 1 and 2, desirably formed integral with the member 43 are a pair of upwardly extending side members 45, 45. Extending between these side members and near 55 the front thereof, as better shown in Figure 1, is a shaft 46 one end of which is threaded and also shouldered, and the other end of which has a slot therein for a screw driver. Both the threaded and unthreaded ends of the shaft 46 60

fit in holes, threaded and unthreaded respectively, in the side members 45, 45.

Referring now to Figure 3, journaled on the shaft 46 so as to be freely rotatable thereon is an abrasive wheel 47 which desirably has teeth 48 resembling ratchet teeth. The abrasive wheel 47 is in contact with the upper end of the pyrophoric metal 41 which is urged against the teeth 48 by means of the spring 39; when the abrasive wheel is rotated in a clockwise direction as viewed in Figure 3, portions of the pyrophoric metal 41 are torn from the body thereof and form a shower of sparks directed to the left in said figure.

Referring now to Figures 2, 3, 6 and 7, there are likewise freely journaled on the shaft 46 a pair of flat side arms 49, 49 forming the forward part of a finger piece member 50. This finger piece member is shown in perspective in Figure 7 and consists of the aforesaid flat side arms 49, 49 joined together by skirt portions 51 and a back 52, the arms, the skirt portions and the back being desirably an integral piece. Resting on the top of the skirt portions 51 and the back 52 is a finger engaging portion 53 which may be fastened to the said skirt and back portion as by soldering. This finger engaging portion 53 closes over part of the space between the two skirt portions 51 and the back wall 52. Referring now to Figure 3, a member 54 is secured to the inside of the skirt portions 51, 51 and the finger portion 53, and all these parts together with the back 52 form a closure 55 for a spring 56. The bottom of the spring 56 fits in a tube 57 held by the irregular supporting member 43, while a rod 58 desirably fits inside the spring 56 extending at least part way up in it in order to prevent said spring from collapsing. It will thus be seen that the spring 56 maintains finger piece 50 in the position shown in Figures 1 and 3, but that said finger piece may be readily depressed to the positions shown in Figures 5 and 6 by pressure on the portion 53. The front ends of the arms 49, 49 are provided with holes 59, 59 through which the shaft 46 passes, and when the finger portion 53 is depressed the entire finger piece 50 swings downwardly about the shaft 46 as a pivot.

On the front of the nearest arm, Figure 7, is a downwardly extending lug 60 the purpose of which will be hereinafter explained. Opposite each other in the arms 49, 49 are a pair of arcuate slots 61, 61, the curve of which is drawn on a radius extending from the pivot shaft 46, and through the slots 61 extends a shaft 62, like the shaft 46, which is supported by the side members 45, 45 and extends between them, its position relative to the entire mechanism being clearly indicated in Figure 1. Upon the shaft 62 is pivotally mounted a snuffer member 63 which carries the snuffer cap 38.

Referring now to Figures 4, 5 and 7, extending inwardly from one of the skirt portions 51 is a latch operating projection 64. This projection 64 may be formed by forcing inwardly part of the metal which constitutes the skirt 51, a cut-away portion 65 being indicated in Figure 4 and representing that part of the skirt portion 51 from which the metal forming the projection 64 was deflected. In this manner manufacture of the complete finger piece 50 is facilitated. Referring to Figure 7, extending inwardly from the arm 49 which is integral with the skirt portion 51 having the projection 64 is an integral lug portion 66 the purpose of which will be hereinafter

explained. This lug portion 66 is made by upsetting the metal inwardly.

The snuffer member 63 hereinbefore referred to is shown in perspective in Figure 8 and in different operating positions in the other figures. It comprises a top portion 67 merging into a pair of downwardly extending side portions 68, 68 at one end, and side portions 69, 69 merging into a rounded downwardly extending front portion 70 at the other end. The side portions 68, 68 of the snuffer member fit between the side portions 49, 49 and the skirts 51, 51 of the finger piece member 50, and the shaft 62 has journaled thereon a sleeve 71 which passes through opposite holes in the sides 68, 68, the sleeve 71 being preferably secured in place by any suitable means, such as by extending the ends thereof.

Referring now to Figures 4, 5 and 8, coiled around the sleeve 71 is a spring 72. One end 73 of the spring 72 extends away from the sleeve 71 and is in contact with the under side of the top portion 67 of the snuffer. The other end of the spring 72 extends in the opposite direction and is turned at right angles forming a portion to be operated 74. Preferably the spring 72 is under tension even when the snuffer is in closed position as shown in Figure 3. The portion to be operated 74 is engaged by the under side of the finger engaging portion 53 when the finger piece 50 is moved downwardly. Prior to the moving downwardly of the finger piece 50 a projection 75 formed integral with the portion 53 and extending forwardly therefrom is in engagement with the under side of the top portion 67 of the finger piece. Under these conditions the spring 72 has no effect upon the snuffer member 63, as whatever couple is exerted by its end 73 is balanced by the couple exerted by the other end 74, through the medium of the projection 75, or in some cases an intermediate portion of the spring 72 may actually be in engagement with the under side of the top portion 67. The moment the projection 75 is removed from the under side of the top portion 67, however, as by moving the finger piece downwardly to the position shown in Figure 5, the tension of the spring 72 is exerted against the snuffer member 63 to swing it upwardly. Thereupon the snuffer member 63 does move upwardly to the position shown in Figure 5 being held there by latch means which will be presently described until the finger piece 50 is moved all the way down, whereupon the latch is tripped and the snuffer flies upward to the position shown in Figure 6.

The lighter of the present invention is adapted to burn solid fuel in the form of a stick of fuel 76 which is received in the tube 27 and urged upwardly by means of a spring 77. The composition of this solid fuel is not the subject of the present application and any fuel which can be ignited by pyrophoric sparks may be used. The tube 30 contains a spare stick of fuel 78 which may be inserted in the tube 27 when the stick 76 is consumed. The snuffer cap 38 is received and held by the snuffer member 63 and has a lower bevel edge 79 which seats upon the seat 37 to prevent evaporation of the fuel. The pawl member 92 fits between the platform 44 and the sparking wheel 47 on one side and the lug 60 on the other side, this lug preventing it from riding off the ratchet wheel 90. The snuffer cap 38 has a bore 80 spaced from a bore 81 by a shoulder 82. In the bore 80 is a cup-shaped member 83 having a bore in its end portion for the reception of the spindle 84 of a catalytic

agent holding member generally designated by the numeral 85. On the lower end of the spindle 84 and just above the catalytic agent 86 is fastened a cage member 87. A spring 88 fits in the cup-shaped member 83 one end of the spring 88 pressing against the inside of the end of the cup-shaped member 83 and the other end pressing against the top of the cage member 87. The cup-shaped member 83 is fastened in place in the bore 80 and the upper part of the bore 80 serves as a bearing surface for a head 89 on the top of the spindle 84. The bore 81 serves as a bearing surface for the cage 87, and thus the member 85 is positioned for limited axial movement in the bores 80 and 81, being held in one extreme position by the shoulder 82 and cage 87 and in the other extreme position by the head 89 and cup-shaped member 83. The spring 88 urges the member 85 downwardly, but said member is held upwardly when the snuffer 38 is down by engagement of the vertical portions of the cage 87 with the flange 36.

Referring to Figure 3, secured to the abrasive wheel 47 at one side thereof is a ratchet wheel 90 which preferably has a very small diameter. Mounted on the inside of the snuffer member 63 on a pin 91 extending between the side portions 69 is a multi-toothed pawl member 92 in engagement with the ratchet wheel 90. The teeth of the pawl 92 are preferably located at the upper end thereof, the lower end being plain, so as to effect rotation of the ratchet wheel only during part of the upward movement of the snuffer. A spring 93 coiled around the pin 91 urges the pawl member 92 into engagement with the ratchet wheel 90.

Referring now to Figure 4, upon the pin 91 which receives the spring 93 is another spring 94 one end of which, like spring 93, is in engagement with the under side of the top portion of the snuffer member, and the other end of which is looped around a latch member 95 which is likewise pivotally mounted on the pin 91 and is urged in the same direction, as regards the snuffer member, as is the multi-toothed pawl member 92. The pawl member 92 and the latch member 95 are located on opposite sides of the platform 44, the platform 44 together with the top wall flange 45 defining slots for these members.

Referring to Figure 8 the latch member 95 is a generally arcuate shape corresponding to the shape of the multi-toothed pawl member 92, and on the inner side of the curve are located a pair of hook-like portions 96 and 97.

The integral lug portion 66 of the finger piece constitutes spacing means to maintain the abrasive wheel 47 away from the front edge of the arm 49, and there is thus defined between said front edge and the abrasive wheel a space in which the curved side of the latch 95 having the hooks 96 and 97 fits, by reason of the tension of the spring 94, and the latch 95 therefore bears against the shaft 46.

The feeding means for the solid fuel comprises the spring 77 and a releasing mechanism which will now be described. Referring to Figures 3 and 4, fastened to the outside of the tube 27 is a flat spring 98 (generically this is a flat spring but actually has a somewhat curved shape as shown) the upper end of which is attached to a detent 99 the shape of which is best shown in Figure 10. The detent 99 comprises a ring 100 extending around the tube 27 and a pair of inwardly projecting latches 101 which extend through holes 102 in the tube 27. A pair of cam

slots 103, 104 are formed in the detent 99 and are engaged by a pair of cam members 105, 106 fastened to the outside of the snuffer cap 38. When the snuffer is down as shown in Figure 3 the cam members 105 and 106 engage the cam slots 103 and 104 and hold the latches 101 away from the solid fuel 76 which is thus free to rise except that it cannot move upwardly beyond the bottom of the catalytic agent 86 which thus forms a stop for the stick of fuel 76. However much fuel may have burned in the previous use of the lighter, so long as there is any fuel left it will rise to the level of the bottom of the catalytic agent 86. Upward movement of the snuffer 38, however, releases the detent 99 and prevents the fuel 76 from flying out of its retaining tube 27 under the influence of the spring 77.

The operation of the lighter is as follows. Downward movement of the finger piece 50 causes the spring 72 to urge the snuffer member 63 upwardly, and the snuffer thereupon rises until the hook portion 96 engages the shaft 46. In rising the snuffer member draws the pawl member 92 over the ratchet wheel 90 and therefore rotates the abrasive wheel 47. During the upward movement of the snuffer cap 38 the catalytic agent holding member 85 moves downwardly with respect to the snuffer cap 38 maintaining the catalytic agent 86 in engagement with the upper end of the fuel 76. Sparks from the pyrophoric member 41 impinge upon the catalytic agent 86 and the fuel 76 simultaneously and ignite the fuel 76. It should be noted that the cage 87 is so formed that the sparks have easy access to the fuel 76, and furthermore the back of the snuffer cap 38 is cut away for the same reason, and the cam members 105 and 106 are spaced apart to allow the sparks to reach the fuel 76. The catalytic agent 86 is shown in the form of a disc, which may be a disc of sponge platinum, platinum black or the like. The catalytic disc, being in contact with the fuel, causes heating of the same until the oxygen inside of the snuffer cap is exhausted. This is a slow combustion and even if the lighter has not been used for a long time it will immediately take place after the snuffer cap is elevated once to introduce a new supply of oxygen into it. The catalytic agent also increases the vapor tension on the surface of the fuel.

When the finger piece 50 is pushed all the way down the latch operating projection 64 strikes the latch 95 and moves the hook portion 96 out of engagement with the shaft 46. Thereupon the snuffer cap 38 flies upwardly to the position shown in Figure 6 and the lighter can now be used to light a cigarette, a cigar, a pipe or anything else. It is noted that the finger piece 50 may be moved downwardly so fast that the two motions of the snuffer will occur one right after the other, and furthermore enough teeth are placed on the pawl member 92 to throw some sparks after the catalytic agent 86 begins to leave the fuel 76. Furthermore downward movement of the catalytic agent holding member 85 maintains it in engagement with the fuel 76 during part of the second movement of the snuffer.

Extra pieces of pyrophoric material 107 are retained in the tube 27.

Figures 11, 12 and 13 are fragmentary views illustrating a modification of the invention involving direct drive from the finger piece to the sparking wheel. According to this modification of the invention the sparking wheel continues to rotate during the time the snuffer is maintained in the position shown in Figure 5. According to

this modification of the invention the pawl 92 may be omitted and pawl teeth 110 provided in one of the side arms 49 of the finger piece 50a. These pawl teeth 110 engage ratchet teeth serrations 111 formed in one side of the sparking wheel 47a. The ratchet teeth serrations 111 take the place of the ratchet wheel 90. Preferably a relatively large sparking wheel 47a is employed in connection with this modification of the invention whereby to obtain a large volume of sparks.

Referring now to Figure 14 there is illustrated a modification of the invention so far as the feeding mechanism for the solid fuel is concerned. The tube 27a is threaded and in it fits a threaded plug 115 supporting a coil spring 116 which is in engagement with the solid fuel. The plug 115 has a bore which is substantially square in cross-section and in which fit a pair of wires 117 desirably formed out of a single piece bent over double, the combined cross-section of the wires 117 loosely fitting the bore in the plug 115. The wires 117 are fastened to a cap 118 which is journaled in the bottom wall 22a of the lighter and has a knurled periphery extending beyond said bottom wall so as to be readily rotatable by means of the fingers. Turning of the cap 118 causes the threaded plug 115 to travel up or down in the tube 27a.

The spring 116 fits over a head 119 provided on the plug 115. This device constitutes manual means for feeding the solid fuel with the spring constituting further feeding means for a limited range. Preferably I provide an escapement mechanism of the type heretofore described in connection with the modification of Figure 14 which, however, may take the simplified form shown in Figure 14.

As shown in Figure 14 the front portion of the tube 27a is cut away to allow a flat spring 120 secured to the outside of the tube 27a to project into engagement with the solid fuel. A spring 120 has a bent-over portion 121 constituting a detent for releasably holding the fuel, and an inclined portion 122 in position to be struck by the edge of the snuffer cap 38a so that the escapement device is in release position when the snuffer is closed as shown in Figure 14. When the snuffer 38a is raised the spring causes the portion 121 to engage the solid fuel holding it from rising further under the influence of the spring 116.

It will thus be seen that there has been provided by this invention an apparatus in which the various objects hereinabove set forth, together with many advantages, are successfully achieved.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a lighter, a casing, pyrophoric spark producing means on the top of said casing, a rod of solid fuel, a tube for said rod of solid fuel, means to feed the solid fuel as it is burned, and a pair of escapement devices arranged to act alternately upon said solid fuel and allow it to be fed by said feeding means as consumed.
2. In a lighter, a rod of solid fuel, a tube for said fuel, means to feed the solid fuel as it is burned, escapement means to control the feeding of said fuel, and spark generating means adapted to throw sparks on the top of the solid fuel.
3. In a lighter, a casing having a top wall, a

finger piece mounted for downward movement on said top wall, a snuffer mounted on said top wall, connections between said finger piece and said snuffer to raise said snuffer when said finger piece is moved downwardly, a sparking wheel, connections between said finger piece and said sparking wheel to rotate the latter from the former, means holding a piece of pyrophoric material in engagement with said wheel, a burner adjacent said wheel, a catalytic agent, and means for maintaining said catalytic agent in engagement with said burner during part of the time that sparks are thrown by said sparking wheel.

4. In a lighter, a burner, a snuffer mounted over said burner, a latch holding a piece of fuel in said burner, connections between said snuffer and said latch to hold the latch out of engagement with the combustible material when the snuffer is down, and spring means to move said latch into engagement with said combustible material when the snuffer is raised.

5. In a lighter, a burner, a snuffer for said burner, a catalytic agent, a holding member for said catalytic agent secured to and mounted for movement with respect to said snuffer, and a spring to project said catalytic agent toward said burner whereby as the snuffer is raised the catalytic agent is automatically lowered to maintain it in engagement with the burner.

6. In a lighter, a holder for a piece of pyrophoric material, a sparking wheel in engagement with said piece of pyrophoric material, means to rotate said sparking wheel, a burner in the path of the sparks generated by said sparking wheel, escapement means associated with said burner, a rod of solid fuel being part of said burner and controlled by said escapement means, and additional means to feed said rod.

7. In a lighter, a burner for solid fuel, means to feed said solid fuel, a snuffer, a downwardly moving finger piece, a catalytic agent carried by said snuffer, means operated by said finger piece to eject sparks onto said burner, said means acting through the entire downward movement of said snuffer, and means to cause said snuffer to be raised a short distance maintaining said catalytic agent in engagement with the solid fuel while the sparks are being thrown and finally upon full depression of said finger piece to move said snuffer rapidly upwardly beyond said position.

8. In a lighter, a parallelopipedal casing, a pair of parallel shafts mounted on top of said casing, a finger piece mounted on one shaft, a snuffer mounted on the other shaft, a tube extending the length of the casing and having an opening at the end thereof nearest the first named shaft, fuel in said tube, spring means urging said finger piece upwardly, a sparking wheel mounted on said first named shaft, a ratchet wheel affixed to said sparking wheel, a tube extending through said casing and having an opening on the top thereof under said sparking wheel, a multoothed pawl carried by said snuffer in engagement with said ratchet wheel whereby upward movement of said snuffer rotates said ratchet wheel and therefore said sparking wheel thereby, throwing sparks in the direction of the first named tube, a spring connection between said finger piece and said snuffer whereby downward movement of said finger piece urges said snuffer upwardly, a latch connected to said snuffer to restrain upward movement thereof beyond an intermediate position, trip means on the finger piece to release the latch at the downward position of said finger piece, a catalytic agent carried by said snuffer, 75

and spring means urging said catalytic agent downwardly with respect to said snuffer.

9. In a lighter mechanism as claimed in claim 8, the combination with the parts therein specified of means to urge the fuel in the first named tube upwardly, and escapement means controlling the feeding of the said fuel in the first named tube.

10. In a lighter, a snuffer having a bore, a snuffer cap coaxial with said bore, a catalytic agent, a carrying member for said catalytic agent mounted for longitudinal movement in said bore, and spring means in said bore projecting said catalytic agent carrying member downwardly.

15 11. In a lighter, a tube for a rod of solid fuel, a rod of solid fuel therein, a spring in said tube, said tube having screw threads on the inside thereof, screw thread feeding means in said tube, a manually engageable wheel, a spline connection between said manually engageable wheel and said screw thread feeding means whereby to feed the solid fuel in said tube, a latch normally engaging said solid fuel, a snuffer to extinguish the flame, and operating portions on the latch and 20 the snuffer respectively to hold said latch out of engagement with said solid fuel when said snuffer is down.

25 12. In a lighter, a rod of solid fuel, a tube for said rod, a spring in said tube, said tube having screw threads on the inside thereof, screw thread feeding means in said tube, a manually engageable wheel, a spline connection between said manually engageable wheel and said screw thread feeding means whereby to feed the solid fuel in 30 said tube, a latch normally engaging said solid fuel, and means to move said latch to allow the fuel to be fed.

35 13. In a lighter mechanism as claimed in claim 8, the combination with the parts therein specified of means to feed the fuel in the first-named tube, and cam means to control the feeding thereof.

40 14. In a lighter mechanism as claimed in claim 8, the combination with the parts therein specified of resilient means in the first-named tube urging the fuel upwardly, a detent restraining the fuel from moving upwardly, and means operated by the snuffer for periodically moving said detent from its restraining position.

45 15. In a lighter, an abrasive wheel, a pyrophoric element, a flame producing burner, a snuffer for said burner, means adapted to remove said snuffer from said burner and rotate said wheel, and a catalytic agent maintained in contact with said burner during a portion of the removal motion of said snuffer from said burner, said abrasive wheel being adapted to throw sparks conjointly upon said catalytic agent and said burner, said catalytic agent being disassociated from said burner when 50 said snuffer ceases its removal motion.

55 16. In a lighter, an inflammable element, a snuffer for said element and removable therefrom, a catalytic agent associated with said snuffer, spark producing means, and means adapted to direct a shower of sparks conjointly upon said inflammable agent and said catalytic agent upon the removal of said snuffer, said catalytic agent being adjacent said inflammable element during a portion of the removal motion 60 of said snuffer and being spaced from said inflammable element when said removal motion ceases.

65 17. In a lighter, means adapted to support com-

bustion, extinguishing means movable toward and away from said first-mentioned means, a catalytic agent associated with said second-mentioned means, and adjacent said first-mentioned means when said extinguishing means rests upon said first-mentioned means and during a portion of its removal motion away therefrom, and means adapted to direct a shower of sparks conjointly upon said first-mentioned means and said catalytic agent upon the removal of said extinguishing means from said combustible means.

70 18. In a lighter, means adapted to support combustion, sparking means for igniting said first-mentioned means, a snuffer for extinguishing said first-mentioned means, said snuffer including a bore, and a catalytic agent reciprocably mounted in said bore and in engagement with said first-mentioned means when said snuffer is positioned thereover and also during a portion of the removal motion of said snuffer away from said first-mentioned means.

75 19. In a lighter, a rod of solid fuel, container means for said fuel, means for feeding said fuel as it is burned, a snuffer adapted to extinguish said fuel and movable toward and away from said fuel, a catalytic agent adjacent said fuel when said snuffer is in extinguishing position and spaced from said fuel during combustion thereof, and spark generating means adapted to direct sparks conjointly upon said catalytic agent and 30 said fuel when said catalytic agent is adjacent said fuel.

80 20. In a lighter, a substantially rigid combustible element, means for igniting said element, means for extinguishing said element, means adapted to facilitate and expedite the ignition of said combustible element, and means actuated by said extinguishing means for feeding said combustible element as portions thereof are burned away.

85 21. In a lighter, a substantially rigid combustible element, means including an igniter and a snuffer for said element, said igniter operating during the motion of said means in one direction and said snuffer fulfilling its function upon the opposite direction of operation of said means, and means for feeding said element subsequent to the burning away of portions thereof, said means including a detent intermittently in engagement with said element and movable out of engagement therewith upon said opposite direction of movement of said first-mentioned means.

90 22. In a lighter, a substantially rigid combustible element, means for igniting said element, means for extinguishing said element, means for feeding said element as portions thereof are burned away, and means intermittently in engagement with said element, said engaging means being movably away from said element by said extinguishing means to permit the feeding thereof.

95 23. In a lighter, a substantially rigid combustible element, means for igniting said element, a snuffer for said element, a catalytic agent mounted in said snuffer and adapted to engage said element when said snuffer rests thereupon and during a portion of the removal motion of said snuffer away from said element, whereby sparks from said igniting means are directed conjointly upon said element and said catalytic agent, and means for intermittently feeding said element.

CARL JULIUS LAGERHOLM.
